UNITED STATES PATENT OFFICE.

CARL J. H. FLINDT, OF BROOKLYN, NEW YORK, ASSIGNOR OF TWO-THIRDS
TO JAMES P. FARRELL, JR., AND EDMUND McMURRAY, OF BROOKLYN,
NEW YORK.

DESIGN FOR A VESSEL'S HULL.

SPECIFICATION forming part of Design No. 35,590, dated January 14, 1902.

Application filed October 15, 1901. Serial No. 78,753. Term of patent 14 years.

To all whom it may concern:

Be it known that I, CARL J. H. FLINDT, a citizen of the United States, and a resident of the borough of Brooklyn, in the city and State of New York, have invented a new and original Design for a Vessel's Hull, of which the following is a specification.

The essential feature of my design consists in the hull of a vessel developed throughout the length of its bottom into separated bilges, with a free arched passage-way between them from bow to stern, the sides of the hull merging naturally into the outer sides of the bilges and the bilges projecting at the rear in tapered form.

In the accompanying drawings, Figure 1 represents the vessel's hull in side elevation.

Fig. 2 represents a bottom plan view of the same, and Fig. 3 is a view in perspective of the stern portion of the hull.

The body of the hull is denoted by *a*, the bilges at the bottom by *b b'*, and the arched passage-way between the bilges by *c*.

What I claim is—

The design for a vessel's hull, substantially as herein shown and described.

In testimony that I claim the foregoing as my invention I have signed my name, in presence of two witnesses, this 12th day of October, 1901.

CARL J. H. FLINDT.

Witnesses:

FREDK. HAYNES,
HENRY THIEME.
